DESIGN FOR A DISPLAY STAND

Paul M. Ressinger, Chicago, Ill.

Application May 19, 1943, Serial No. 110,237

Term of patent 14 years

To all whom it may concern:

Be it known that I, Paul M. Ressinger, a citizen of the United States, residing at Chicago, in the county of Cook and State of Illinois, have invented a new, original, and ornamental Design for a Display Stand, of which the following is a specification, reference being had to the accompanying drawing, forming part hereof.

I claim:

The ornamental design for a display stand, as shown.

PAUL M. RESSINGER.
